UNITED STATES PATENT OFFICE

2,439,787

ULTRAVIOLET RAY GENERATOR

Carl E. Atkins, Elgin, Ill., assignor to Sun-Kraft,
Inc., Chicago, Ill., a corporation of Delaware

Application February 5, 1945, Serial No. 576,303

6 Claims. (Cl. 128—395)

1

This invention relates to internal ultra-violet ray therapy, and more particularly to an applicator tube and a circuit for energizing the same.

It is a principal object of the invention to produce or generate ultra-violet ray energy in a slender elongated quartz tube which may be easily inserted into a body orifice for medical treatment under the direction of a physician.

Electrodeless ultra-violet ray tubes have previously been employed for internal therapy, but these have been of limited utility because of the great difficulty in maintaining ionization of the vapor in the tube throughout the entire length of the tube. In previous devices of this kind the glow produced by ionization of the vapor retreats toward the remote or external end of the tube as the same is introduced into the patient's body. It is accordingly an object of the invention to provide an ultra-violet ray generator of the type described and in which the ionization of the vapor in the tube is substantially unaffected by its introduction into the patient's body.

In previous units of this type, the ionization of the vapor in the tube and hence the intensity of the ultra-violet ray generated by such ionization is subject to capricious body-capacity effects resulting from its handling by the operator or physician and it is difficult under such circumstances to initiate or to start the ionization process. In such previous devices the applicator tube was surrounded in its insulating handle with a coil of wire supplied with energy from a suitable oscillator circuit. When the handle was grasped by an operator the thus introduced body capacity served to divert a large portion of the energy away from the applicator tube, thus making it difficult to start the ionization process and materially reducing it, if it had already been started. This electromagnetic transfer of energy is, moreover, highly inefficient for, as my experiments have demonstrated, the energy was transferred to the ionization discharge by electrostatic field rather than electromagnetic field, and the electromagnetic coil functioned to feed energy into the discharge only, as it provided some measure of an electrostatic field. It is accordingly an object of my invention to provide an ultra-violet ray generator of the type described wherein the body capacity effects are eliminated or minimized; ionization readily initiated and maintained, and the efficiency of the energy transfer materially improved.

Other and further objects and advantages of the invention will be apparent from the following description when taken in connection with the

2

accompanying drawing, wherein the single figure is a schematic diagram of the circuit and applicator tube embodying the invention.

As shown in the drawing, the applicator tube 5 comprises a thin, pencil-like quartz tube 2 closed at one end and at its other end joined to or integrally formed with a relatively large bulb 4. The applicator tube is sealed at its opposite ends and contains a globule of mercury and a mixture of rare gases at any suitable low pressure, as, for example, a pressure of ten millimeters of mercury. The large bulb-like end 4 of the tube is mounted or secured in an insulating housing 6 which may be constructed of Bakelite, polystyrene or any similar dielectric material having good high frequency characteristics and the required mechanical properties. A metal band 8 encircles and engages the large bulb-like end 4 of the quartz tube and is connected to the wire 10 by transmission line or cable 12, the other wire 14 of which enters the housing 6 and is mechanically fastened or secured to the inner surface of this housing at a point proximate the metal band 8.

25 The cable or transmission line 12 is of relatively non-critical length—for example, from between three and seven feet long.

The equivalent of effective capacity of the lamp, or terminating end of the transmission line 30 12, and the line, forms part of the tuning capacity of a high frequency oscillator circuit 16 operating on a frequency between twenty and one hundred megacycles.

35 The oscillator or generator 16 comprises a rectifier tube or diode 18 having its filament 20 connected by wires 22 and 24 to the alternating current supply lines L1 and L2 and its plate 26 connected by wire 28 to the supply line L1. The cathode 30 of the diode 18 is connected through 40 electrolytic power condenser 32 to the supply line L2. It is also connected by wire 34 to the screen grid 36 of a power tetrode 38 and through wire 40 to the screen grid 42 of a second power tetrode 44 connected in push-pull relation with the tube 38.

45 The plates 46 and 48 of the tetrodes 38 and 44 are connected to the opposite ends of the tank circuit inductance 50 which has its mid-point 52 connected, as by wire 54, to the screen grid 42 and thence by wires 40 and 34 to the screen grid 36 of the tube 38 and the cathode 30 of the tube 18. The control grids 56 and 58 of the tubes 38 and 44 are cross connected through the grid blocking condensers 60 and 62 and wires 64 and 66 to intermediate taps on the tank coil 50.

55 The cathodes 68 and 70 of the tubes 38 and 44

are connected to the control grids of the same tubes through the usual grid resistors 72 and 74 and are directly connected to the supply line L2.

The filaments of the tetrodes are connected in series and through wires 76, 78 and 80 to the supply lines L1 and L2. The transmission line 12 is connected through blocking condensers 82 and 84 to the opposite ends of the tank coil 50.

The oscillator or generator 16 may be mounted or enclosed in any desired form of metal housing, preferably a metal housing constructed as shown in the patent of Frank Furedy No. 2,327,-346. This metal housing (not shown) constitutes a relatively large conductor and functions as a radiation member. It is employed as a counterpoise to improve greatly the performance of the applicator tube and, for this purpose, the metal housing counterpoise 86 is connected to the control grid 58 of tetrode 44 through a coupling condenser 88.

The coupling condenser 88 ties the counterpoise 86 to the radio frequency circuit and since there is substantial electrostatic coupling, energy supplied to the discharge tube from the band 8 is transmitted through the patient's body and back to the metal housing counterpoise 86, and thence through the coupling condenser 88 back to the oscillator. This arrangement not only increases the intensity of the discharge in tube 44 but by establishing a balance with its sibling (the other half of the transmission line through which a portion of the energy returns to the oscillator) helps to reduce operator hand or body capacity effects and aids in the initiation of the glow discharge in the applicator tube.

It is preferred to employ as a rectifier a 117-Z4GT diode and as oscillator tubes 50L6GT power tetrodes.

The electrolytic condenser 32 may have a value of from four to thirty micro-farads, while the grid blocking condensers 60 and 62 are preferably on the order of two hundred and fifty micro-farads, and the grid resistors 72 and 74 of 10,000 ohms each. The coil 50 should be of an inductance such as to tune the oscillator to a frequency within the heretofore stated range of between twenty and one hundred megacycles.

It will be seen from the foregoing description that applicant has provided an ultra-violet ray generator which employs a slender elongated, electrodeless quartz tube that may be easily inserted into a body orifice for medical treatment under the direction of a physician; and by means of which ionization of the vapor in the tube is readily initiated and maintained and the efficiency of the energy transfer materially improved.

It is obvious that various changes may be made in the specific embodiment of the invention set forth for the purposes of illustration without departing from the spirit of the invention. Accordingly the invention is not to be limited to the specific embodiment shown and described but only as indicated in the following claims.

What I claim is:

1. An ultra-violet ray generator comprising an electrodeless vapor discharge tube, a metal band about a portion of said tube, an insulating member encircling said band but in spaced relation thereto, a wire connected to said band and extending from said member and a second wire entering said member and secured to the inner surface thereof, and means for supplying high frequency energy to said wires.

2. An ultra-violet ray generator comprising an

electrodeless vapor discharge tube having an elongated small diameter portion for internal therapy and a substantially larger tubular end portion, a handle housing of insulating material enclosing said larger tubular portion, a metal band encircling said larger tubular portion within said housing, a wire connected to said band and extending out of said housing, a second wire secured to the inner surface of said housing proximate said band and extending out of said housing, and means for supplying high frequency energy to said wires.

3. An ultra-violet ray generator comprising an electrodeless ultra-violet ray tube, a metal band encircling a portion of said tube, a relatively low power oscillator having a tank coil connected to said band, a counterpoise capacitively coupled to said coil and cooperating with said band to supply energy from said oscillator to said tube by electrostatic coupling.

4. An ultra-violet ray generator comprising an oscillator having supply circuits and a high frequency radio frequency generation circuit, a metal housing for said oscillator, an ultra-violet vapor discharge tube, a metal band encircling a portion of said tube and connected to the radio frequency circuit, and a coupling between said housing and said radio frequency circuit of the oscillator whereby energy is fed electrostatically to said tube through said metal housing and said band.

5. An ultra-violet ray generator for internal ray therapy comprising a vapor discharge tube having an elongated narrow tubular portion for insertion in a body orifice and a large tubular portion in vapor communication with said first-mentioned portion, a handle housing of insulating material enclosing said large tubular portion, a metal band in said housing and encircling said large tubular portion, a wire connected to said band and extending out of said housing, a high frequency oscillator connected to said wire, a second wire connected to said oscillator, extending into said housing and secured to the inner surface thereof proximate the metal band, and a counterpoise coupled to said oscillator to establish a balance with the connection of said second wire to the oscillator and the handle housing thereby to reduce the capacity effect of the handling of said housing.

6. An ultra-violet ray generator comprising a body applicator tube having a pencil-like elongated tubular portion for insertion in a body orifice and a large tubular portion integral therewith and in internal communication with said first-mentioned portion, an insulating handle member encircling said enlarged portion, a metal band in said handle member and encircling in contact relation said large tubular portion, a high frequency oscillator having a wire connection to said band, and a counterpoise coupled thereto for supplying energy by electrostatic coupling to said tube.
